CLAIM

The ornamental design for a child head support, as shown and described.

DESCRIPTION

FIG. 1 is a perspective view of a child head support, showing my new design;

FIG. 2 is a front elevational view of the child head support thereof;

FIG. 3 is a rear elevational view of the child head support thereof;

FIG. 4 is a left side elevational view of the child head support thereof;

FIG. 5 is a right side elevational view of the child head support thereof;

FIG. 6 is a top plan view of the child head support thereof;

FIG. 7 is a bottom plan view of the child head support thereof; and,

FIG. 8 is a perspective view of the child head support thereof, shown in a state of use with environment.

The dashed lines in FIGS. 1-7 depict stitching that forms part of the claimed design. The larger dashed broken lines in FIG. 8 showing a car seat depict environment that forms no part of the claimed design. The dash dot broken lines depict portions of the article that form no part of the claimed design.

1 Claim, 4 Drawing Sheets
